UNITED STATES PATENT OFFICE

171,548

ESCUTCHEON PLATE FOR TELEVISION RECEIVERS

Richard C. Marholz, Chicago, Ill., assignor to Raytheon Manufacturing Company, a corporation of Delaware

Application September 24, 1952, Serial No. 21,559

Term of patent 3½ years

(Cl. D56—4)

To all whom it may concern:

Be it known that I, Richard C. Marholz, a citizen of the United States, residing at Chicago, in the county of Cook, State of Illinois, have invented a new, original, and ornamental Design for an Escutcheon Plate for Television Receivers, of which the following is a specification, reference being had to the accompanying drawing, forming a part thereof, in which:

Figure 1 is a front elevational view of an escutcheon plate for television receivers showing my new design;

Figure 2 is a bottom plan view thereof;

Figure 3 is a side elevational view thereof; and

Figure 4 is an enlarged sectional view thereof taken on line 4—4 of Fig. 1.

I claim:

The ornamental design for an escutcheon plate for television receivers, substantially as shown.

RICHARD C. MARHOLZ.
